UNITED STATES PATENT OFFICE.

JAMES CARLTON, OF WILLOW, CALIFORNIA, ASSIGNOR OF ONE-HALF TO
E. M. TYLER, OF SAME PLACE.

ADJUSTABLE ELEVATOR-SUPPORT FOR DERRICK-WAGONS.

SPECIFICATION forming part of Letters Patent No. 319,066, dated June 2, 1885.

Application filed April 9, 1885. (No model.)

To all whom it may concern:

Be it known that I, JAMES CARLTON, of Willow, Colusa county, State of California, have invented an Improvement in Adjustable Elevator-Supports for Derrick-Wagons; and I hereby declare the following to be a full, clear, and exact description of the same.

My invention relates to a new and useful vertically-adjustable and traveling elevator-support for a derrick-wagon.

My invention consists in a vertical frame, in the sides of which a cross head or rest is mounted, and adapted to be vertically adjusted by means of an adjustable lever and connecting-links, and in a supplementary axle provided with a bolster, on which the vertical frame is supported, said axle being attached to the rear axle of the derrick-wagon by means of pivoted cross-reaches and a connecting-bar, whereby the whole device becomes a part of the derrick-wagon and accompanies it.

The object of my invention is to provide a permanent support for the elevator, adapted to adjust it to a suitable inclination, and thus to avoid the labor required to ship and unship the elevator and place it in position.

Referring to the accompanying drawing, the figure is a perspective view of my elevator-support.

A is a vertical frame, which may be constructed in any suitable manner, though preferably of two gas-pipe standards, *a*, and a cross top piece, *a'*, also of gas-pipe, connected with the standards by elbows *a''*. B is the cross head or support. It consists of a bar extending transversely between the standards, and having grooves *b* in its ends, by which it is fitted upon said standards, and is adapted to move vertically thereon. It is held to its place by straps *b'*, embracing standards *a*. The lower portion of the frame A is secured upon a bolster, C, in a manner which I shall hereinafter describe.

D is a slotted standard, in which is pivoted a lever, E, the short arm of which is connected by links *e* with the cross-head. By operating the lever E the cross-head is moved up and down on its side guides. The links *e* are secured to the cross-head by means of eye-bearings *e'*, in which they are pivoted, said bear-

ings being seated in angle-bars *e''*, secured to the cross-head and acting as guides on the sides *a*.

F is a portion of the rear of a derrick-wagon, which is made of the usual form, having a rear axle, G.

H is a supplementary wheeled axle.

I are cross-reaches pivoted to the rear axle, G, of the derrick-wagon, and to the supplementary wheeled axle.

Pivoted by a king-bolt, J, on the top of the supplementary axle is the bolster C, which is connected with the rear axle of the derrick-wagon by a reach or connecting-bar, K, which is pivoted in the block or bed of the rear axle.

Upon the bolster C is secured by bolts *l* the two-part piece L. This piece receives the standards *a* of the frame A, and clamps them by means of the bolts *l'*. The elevator N (which is here shown in dotted lines) extends from the derrick-wagon to the cross-head B, and rests thereon. Ordinarily the elevator has to be shipped and unshipped from the feeder, and as it is very heavy (weighing about one thousand pounds) it requires the whole crew to manipulate it. Whenever it is to be placed in position ready for work, it has to be pulled back off of the derrick-wagon and supported in some way above the feeder, (unnecessary herein to show,) to which it carries its load.

The advantage of my device is, that, being connected with the derrick-wagon, the elevator may be left permanently in position, and thus carried around with the wagon. By the manipulation of the lever E the discharge end of the elevator may be raised or lowered at will, and the limits of motion may be defined by means of a series of holes, *m*, made in the lever, by which the movement of its short arm may be increased or diminished by pivoting it in various holes of the series. The peculiar connection between the device and the derrick-wagon enables it to be always brought to and to remain in proper and accurate position.

I am aware that it is not new in wagons to connect the axles by pivoted cross-reaches, and I do not herein wish to claim such, broadly, my invention in this respect being in the attachment to the derrick-wagon in this manner

of a supplementary wheeled axle carrying the vertically-adjustable support. When the cross-head is down to its limit, the links *e* rest upon the center of bolster *C*, and act as braces 5 to support the weight.

Having thus described my invention, what I claim as new, and desire to secure by Letters Patent, is—

1. An adjustable support for the rear end 10 of the elevator of a feeder, consisting of the base-piece *L*, the frame *A*, supported by said base-piece, the moving cross head or bar *B*, mounted between the sides of the frame, and the means for vertically adjusting said cross-head, consisting of the lever *E*, pivoted in the standard *D*, supported by the base-piece, and the links *e*, connecting the lever with the cross-head, substantially as herein described.

2. A device for supporting the rear end 20 of the elevator of a feeder, consisting of the base-piece *L*, the frame *A*, supported thereon, the cross-head *B*, sliding within and guided by the frame, the slotted standard *D*, the lever *E*, provided with a series of holes, *m*, by which 25 it may be adjustably pivoted in the standard *D*, and the links *e*, connecting the lever with the cross-head, substantially as herein described.

3. In a device for supporting the elevator 30 of a feeder, the frame *A*, consisting of gas-pipe standards *a*, and gas-pipe cross-head *a'*, connected with the sides of the frame by elbows, the two-part base-piece *L*, receiving the gas-pipe side pieces, and the clamping-bolts *t'*, by 35 which the two-part base-piece is made to bind and secure the frame *A*, in combination with the vertically-adjustable cross-head *B*, mounted upon and between the side standards of the said frame, substantially as herein described.

4. The supplementary wheeled axle *H*, connected with the derrick-wagon, and the bolster *C* on said axle, in combination with the frame *A*, secured to the bolster, and the ver-

tically-adjustable cross-head *B* in the frame 45 *A*, substantially as herein described.

5. The supplementary wheeled axle *H*, connected or attached to the rear of the derrick-wagon, and the bolster *C* on said axle, in combination with the two-part base-piece *L*, secured by bolts *l* to the bolster, the frame *A*, clamped by said base-piece, the cross-head *B* in the frame, the lever *E*, and links *e*, by which the cross-head is vertically adjusted, substantially as herein described. 55

6. In combination with the derrick-wagon *F*, having a rear axle, *G*, and an elevator, *N*, as described, the supplementary wheeled axle *H*, connected with the rear axle of the derrick-wagon, the bolster *C* on the supplementary 60 axle, the frame *A*, secured to the bolster, and the vertically-adjustable cross head or rest *B* in the frame and adapted to support the rear end of the elevator, substantially as herein described. 65

7. In combination with the derrick-wagon having a rear axle and an elevator, the supplementary wheeled axle *H*, having a pivoted bolster, *C*, the frame *A*, secured to the bolster, the sliding cross head or rest *B* 70 in the frame, and the lever *E* and links *e*, by which said cross-head is vertically adjusted, and the means by which the supplementary axle is connected with the derrick-wagon, consisting of the cross-reaches *I*, pivoted to the 75 supplementary axle and to the rear axle of the derrick-wagon, and the connecting-bar *K*, secured to the bolster *C* and pivoted to the rear axle-bed of the derrick-wagon, all arranged and adapted to operate substantially 80 as herein described.

In witness whereof I have hereunto set my hand.

JAMES CARLTON.
